Specification of Letters Patent.

Patented Dec. 18, 1917.

Application filed June 24, 1912. Serial No. 705,365.

To all whom it may concern:

Be it known that I, HENRY H. MERCER, a citizen of the United States, and a resident of Claremont, county of Sullivan, State of 5 New Hampshire, whose post-office address is Claremont, New Hampshire, have invented an Improvement in Stoneworking-Machines, of which the following description, in connection with the accompanying drawings, 10 is a specification, like characters on the drawings representing like parts.

This invention relates to stone working machines and more particularly, though not exclusively, to machines of the channeling 15 type, the object of the present invention being to provide a simple but efficient stone cutting apparatus.

The invention, as herein shown for illustrative purposes, is embodied in a machine 20 for cutting not only the main portion of the channel groove, but also the end thereof which extends under an overlying side wall of the quarry. The invention, however, as to many of its features may be usefully applied 25 to other forms of machines than the one herein shown.

The invention will be best understood by reference to the following description when taken in connection with the accompanying 30 illustration of one specific embodiment thereof, while its scope will be more particularly pointed out in the appended claims.

In the drawings:

Fig. 1 is a front elevation of a channeling 35 machine embodying one form of the invention;

Fig. 2 is a view on a smaller scale showing a different position of the truck when employed for corner cutting;

Fig. 3 is an end view of the rail clamp shown in Fig. 1;

Fig. 4 is a plan view showing the channeling machine of Fig. 1 with its standard in section and the cutting unit parts removed 45 therefrom;

Fig. 4^a shows a detail of the support for the tool feed gearing;

Fig. 5 is a sectional elevation on an enlarged scale showing the details of the axial 50 brace rod for the standard;

Fig. 6 is an end view of the channeling machine shown in Fig. 1, certain parts thereof being removed for the sake of clearness;

Fig. 7 is an elevation in section showing details of the truck driving gears; and 55

Fig. 8 is a sectional elevation on the line 8—8 in Fig. 7.

Referring to the drawings and to the machine shown therein, while the invention may be embodied in machines and devices 60 other than the specific type herein shown, for the sake of illustration there is shown one embodiment of the invention in a track channeler of common construction, the same consisting of a main truck support or frame 65 mounted upon the truck wheels 2, the latter adapted to travel along the trackway 3 customarily laid along the quarry bottom.

As is usual in this class of devices, the truck is self-propelled by a suitable motor 70 (Fig. 4) such, for example, as the steam or air engine 4 which is mounted on the truck and is adapted to drive the same through appropriate driving mechanism. Herein a common form of driving mechanism is em- 75

ployed, as follows: Connected to the crank shaft 5 of the engine is a beveled driving gear 6 meshing with the gears 7 and 8, the latter being loose upon the countershaft 9 but adapted either one to be clutched thereto 80 by the sliding clutch members 10 and 11 re- spectively. The latter are moved simulta- 85

neously by the slide rod 12 and lever 13 so that either the gear 7 or the gear 8 may be clutched at will to drive the countershaft 9 85

and therefore turn the latter in either direction. The countershaft carries at one end the larger gear 14 and the relatively smaller gear 15 which are employed, one or the other

according to the use to which the machine is 90 put, to drive, through suitable intermediate gearing to be more fully described, a gear 16, the latter adjustably secured to the truck driving shaft 17, which is connected to drive the axles 18 and the wheels 2 through the 95

worm gearing 19. By this mechanism the operator can drive the truck in either direction, hold the same fixed, or reverse its movement at will.

The machine illustrated is provided with 100

the usual form of tool carrier or standard 20 mounted at the side of the truck, herein upon the standard-carrying bracket 21 (Figs. 4 and 6) the latter being split and 5 adapted to be adjustably positioned and clamped upon the trunnion bar 22 at either end of the truck.

Any desired form or construction of channelling tool or motor may be employed, but 10 herein there is illustrated a common form of compressed air channelling engine 23 having rigidly secured to the cylinder thereof cross-head guides 24, the two constituting a sliding frame adjustable lengthwise the 15 standard as is customary, through the medium of the feed screw 25.

Any suitable means may be employed to turn the feed screw, but herein there are provided loose upon the truck driving shaft 20 17 gears 26 and 27 (Fig. 4), these being driven in opposite directions by engagement with gears 7 and 8, respectively. The gears 26 and 27 may be separately clutched to or unclutched from a sleeve 30 on which the 25 beveled gear 28 is fixed, which gear meshes with a beveled gear 29, the latter having suitable connections to turn the feed screw.

Either one of the gears 26 or 27, which, it 30 will be observed, are continuously rotated in opposite directions, may be clutched to the sleeve 30 of the beveled gear, sliding clutch members 31 and 32 being provided for that purpose. The clutch members are moved simultaneously by means of the sliding rod 33 and the lever 34. When the lever and rod are thrown to one position, the gear 26 is clutched to the sleeve 30, turning the feed gear 29 in one direction. When lever and rod are moved to the opposite extreme, the 40 gear 26 is unclutched from the sleeve and the gear 27 clutched thereto rotating the gear 29 in the opposite direction. In an intermediate position, such as is shown in Fig. 4, both gears are unclutched and the 45 feed screw remains fixed. The beveled gear 29 is herein journaled upon a bracket or box 35 which latter is adjustably clamped in suitable arc-shaped ways (see Fig. 4^a), so that it may be placed in operative relation to the beveled gear 28 in all positions of the standard. The beveled gear 29 has secured thereto for rotation therewith the sprocket wheel 36 over which passes the feed sprocket 50 chain 37.

55 To permit the various angular adjustments of the standard, as well as the swinging movement thereof when required for corner cutting, without interference with the tool feeding mechanism, the feed sprocket 60 chain is caused to pass over suitable guiding sprocket wheels 38 and 39 and thence to a sprocket wheel 40, the latter being arranged co-axially with the standard as will be more fully referred to. The guiding 65 sprocket wheels 38 and 39 are carried by a

bracket or frame 41 which is adjustably clamped to the trunnion bar 22 so that its position may be adjusted and the proper tension and direction of the feeding chain at all times maintained. The sprocket wheel 40 (Fig. 5) is mounted upon the sleeve 42 with its companion sprocket wheel 43, the sleeve being journaled upon the axial member or brace rod 44. The sprocket wheel 43 engages and drives the second feed chain 45, 70 the latter passing up and over the sprocket wheel 46. The sprocket wheel 46 is connected to drive the beveled gears 47 and 48 and the feed screw 25. The chain 45 is kept under suitable tension by means of the 80 idle sprocket wheel 49 carried by the arm 50 adjustably secured to the standard.

From the described connections, it will be seen that the feed screw may be turned at will in either direction irrespective of the 85 direction of movement of the truck or whether the truck is at rest or in motion. It will also be seen that the bracket 41 may be adjusted to correspond to any inclined adjustment of the standard and that, the 90 sprocket wheels 40 and 43 being co-axial with the standard, the feed is effective irrespective of whether the standard is fixed or undergoing the swinging movement hereinafter referred to.

95 Referring again to the tool-actuating engine 23, the piston rod 51 thereof is secured to a cross-head 52, the latter adapted to slide in the cross-head guides 24 and having attached thereto the tool or tools 53 constituting the channelling gang.

The described form of channeler may be employed in the usual way in cutting an ordinary channel groove. That is to say, the standard may be clamped in fixed position 100 on the truck (as, for example, the position shown in Fig. 1, but without the connections to the rails therein shown); one or more of the customary brace members being employed to hold the standard rigid.

110 When it is required to cut the corner or the end of the channel groove, the brace member or members are removed and the standard, which has a pivotal connection to the bracket 21 is loosened so as to be free 115 to turn about its pivot. The truck is arranged on the trackway with relation to the quarry in some such position as is represented in Fig. 2 and there is then connected to some part of the tool carrier, preferably 120 near the upper part of the standard, as at 54, a link 55 or other suitable attachment member, the opposite end of which has jointed connection to some point fixed relatively to the truck or having a movement different from that of the truck. Herein the opposite end of the link is fastened to an eye bolt 56, the shank of which is securely clamped between the split halves of the rail 125 clamp 57 which latter is provided with the 130

jaws 58 adapted to grip the flange of the rails 3.

With the parts thus connected, the truck driving motor can be thrown into connection with the truck driving mechanism by means of the lever 13 to advance the truck just as in traversing the same for cutting the usual channel groove. The truck then moves in toward the overhanging wall of the quarry from the position shown in Fig. 1 to that shown in Fig. 2, carrying the pivotal support of the standard with it. The upper part of the standard, however, being held back relatively to the pivotal point, causes the tool gang to swing or move from the position shown in Fig. 1 to that shown in Fig. 2, the cutting edges describing a path which may be similar to that indicated in Fig. 2 and is suitable for cutting under the overhanging side wall of the quarry. The top of the standard swings back during this movement to the inclined position shown in Fig. 2 so that the truck is permitted to move close in under the overhanging side wall and secure the full benefit of the forward reach of the gang. When the inward extreme limit of movement has been reached, the truck driving mechanism can be reversed to swing the standard back to the position shown in Fig. 1, this cycle of movement being repeated again and again and the tool being fed slowly forward by means of the feed screw until the required depth of cut has been reached.

While it is convenient to utilize the truck driving mechanism itself for swinging or moving the tools for corner cutting as well as to move the truck for cutting in the open, the speed of truck travel which is appropriate for cutting the ordinary channel groove is somewhat too great for best results where the truck movement is employed to swing the tool for corner cutting. While the truck driving mechanism herein is preferably employed in corner cutting for moving the pivot support of the standard, there is also preferably employed speed reducing mechanism whereby the reciprocatory travel of the truck under such circumstances can be made to take place at a less rate of speed than the travel of the truck when cutting in the open.

In the embodiment herein disclosed, such speed reducing mechanism comprehends change gears interposed between the countershaft 9 and the truck driving shaft 17. During the travel of the truck required for cutting the ordinary channel groove, the relatively higher rate of truck travel is obtained by adjusting the gear 16 on the shaft 17 to a position where it meshes with the gear 14 on the countershaft 9. The gear 16 for that purpose is mounted upon a split hub 59 so that it can be unclamped and shifted to different positions lengthwise of the shaft.

When moved to a position to mesh with the gear 14, the truck driving shaft is driven directly from the countershaft at the high rate of speed.

During reciprocatory travel of the truck required for the tool swinging movement, a relatively slow movement of the truck is secured as follows: The gear 16 on the truck driving shaft is adjusted to mesh with the small pinion 60, the latter being integral with and driven by the larger gear 61 which meshes in turn with the smaller driving pinion 15. This speed reduction arrangement is represented in Fig. 7. The gears 60 and 61 are cast together and turn upon a quill or bushing 62. The gears and the quill are held in a fixed position by means of the bolt 63 upon a bracket 64 fastened to the truck by means of the bolts 65. The bracket 64 receiving the bolt 63 has a slot 66, the latter being arc-shaped with the axis of the shaft 9 as a center. The quill 62 is provided with a pair of pins 67 which fit holes 68 on either side of the slot 66, a series of such holes being provided so that the quill may be adjusted and clamped in different, but well defined and predetermined, positions in the bracket. By means of this sleeve different dimensions of change gears may be employed in substitution for the gears 60 and 61 and the speed of truck movement changed to suit the peculiar requirements of any case. In the illustrated form of machine, six sets of openings 68 are provided to correspond to six different sets of change gears.

It is frequently desirable to cut a corner or perform the tool swinging movement with the standard and tools tipped at an angle to the vertical, as represented in dotted line 105 in Fig. 6. The illustrated machine, therefore, is equipped not only with the usual appliances for adjusting the standard to cutting an oblique channel groove in the open, but also for adjusting the plane of swinging 110 movement so that the groove which is initially cut with the standard fixed in an oblique position can be completed by the combined swinging and cutting movement of the tool in the same oblique plane.

Referring to Fig. 5, the standard is carried upon a cone-shaped bearing sleeve 69 which in turn passes through the split clamping bracket 21 and at its outer or smaller end is provided with threads which are engaged by the split clamping nut 70. The fixed axial brace rod 44 passes through the center of the sleeve 69.

When it is required to swing the tool, the nut 70 is loosened, freeing the standard on its cone bearing and the bolt 71 for the bearing, block 21 is tightened to hold the sleeve 69 fast. When it is desired to hold the standard fixed against swinging, the bolt 71 is loosened and the nut 70 is tightened so as 130

to draw the tapered walls of the sleeve 69 tightly in against the bushing 72, the latter being fixed in the standard. The sleeve 69 therefore constitutes a pivotal support upon which the cutting appliances, including the standard and the tool gang carried thereby, are pivoted.

The rear end of the axial brace rod 44 (see Figs. 4 and 5) is adjustably secured to the fixed frame brace 75 by the following means: 10 On the end of the axial brace rod there is clamped by means of the clamping bolt 76 the horizontally split clamp hanger 77. The clamp hanger is transversely perforated to 15 receive the clamping bolt 78, which has threaded engagement with the clamping nut 79, the latter having the shoe 80 fitting the arc-shaped slot 81 in the frame brace 75. The slot 81 is curved about the axis of the 20 trunnion shaft 22 as a center so that by means of the clamping bolt 78 and the nut 79 the rear of the axial brace rod may be adjusted and held fixed in any desired angular position to accommodate the tipped 25 position of the standard. Between the clamp hanger 77, which may be adjustably clamped in different positions on the brace rod 44, and the adjustable clamp collar 82 there is held fixed the back brace swivel 30 block 83 consisting of a sleeve having an upwardly directed lug on which the lower end of the brace rod 84 is swiveled. The brace rod 84 is telescopically adjustable and has jointed connection at its upper end to the 35 standard 20.

It will be seen that the standard can be tipped back to any inclined position and the machine can be used to cut a channel groove with the standard held fixed in such position 40 or while the same is caused to oscillate, the power-actuated feed of the tool being maintained both during the swinging movement of the tool and the fixed position of the standard irrespective of the angle to which 45 the latter may be inclined. It will be obvious that the invention herein as to its broad features is not limited to its embodiment in track channelers or in channeling machines of any specific type, nor is it limited for all 50 purposes to the connection of the tool to a point extraneous to the truck or other movable support employed.

While I have herein shown and described for purposes of illustration one specific embodiment of the invention, it is to be understood that the latter is not limited to the details of construction herein shown nor to the application of the invention herein illustrated nor to the specific form of machine 60 to which the same is shown as applied, but that extensive deviations may be made therefrom without departing from the spirit of the invention.

Claims:

65 1. In a channeler, the combination with

a tool support upon which the tool is pivoted, of means for reciprocatively swinging the tool about its support, and power-driven means for feeding the tool including a power-transmission member mounted to 70 turn about an axis coinciding with the pivotal support of the tool.

2. In a channeler, the combination with a tool support on which the tool is pivoted, of means for reciprocatively swinging the 75 tool upon its support, and tool feeding means including a power transmission member having an axis coinciding with the axis of the pivotal support of the tool.

3. In a channeler, the combination with 80 a truck, of a standard for carrying the tool or tools, said standard having a support upon which the same is mounted to turn about a transverse axis, tool feeding means including a feed screw, and power transmission mechanism for turning said feed screw including a power transmission member mounted to turn about an axis coinciding with the axis of the pivotal support of the standard. 90

4. In a channeler, the combination with a main frame, of a standard, connecting means for pivotally connecting the standard near the base thereof to the main frame for movement about a transverse axis, tool 95 feeding means including a feed screw, and driving connections for turning the feed screw including driving members carried by the standard near the point of its connection to the frame, whereby said connections may 100 be maintained in different positions of adjustment of said standard on its pivotal support.

5. In a channeler, the combination with a truck having a trunnion bar at the side 105 thereof, of a pivotally connected standard mounted for tipping adjustment upon said trunnion bar and for movement about a transverse axis, a feed screw, power transmission devices for transmitting a turning 110 movement to the feed screw, said devices being fixed relatively to the standard to tip therewith, and a motor mounted on the truck independent of said standard for driving said devices. 115

6. In a channeler, the combination with a main frame, of a standard, connecting means for pivotally connecting the standard near the base thereof to the main frame for movement about a transverse axis, tool feeding 120 means including a feed screw, power transmission mechanism for turning said feed screw including a driving member carried by the standard near the point of its connection to the frame, a motor mounted on 125 the truck independent of said standard, and flexible power connections between said motor and said driving member.

7. In a channeler, the combination with a truck having a trunnion bar at the side there- 130

- of, of a pivotally connected standard mounted for tipping movement upon said trunnion bar and for movement about a transverse axis, cutting appliances, a feed screw for 5 feeding the cutting appliances toward or from the work, power transmission devices fixed relatively to the standard to tip there-with for transmitting a turning movement to the feed screw, and additional power 10 driven devices carried by said trunnion bar for transmitting turning movement through said power transmission devices.
8. In a channeler, the combination with a truck, truck driving mechanism, tool feeding mechanism on the truck, a pivoted standard, tool feeding mechanism on the standard including a feed screw, a tool feed driving member near the top of the standard, a tool feed driving member at the bottom 15 of the standard and oscillating with the standard, driving connections between said upper and lower tool feed driving members, and driving connections between said lower tool feed driving member and 20 said tool feeding mechanism on the truck.
9. In a channeler, the combination with a truck, of a standard pivotally supported thereon, an axial member alined with the pivotal support of said standard, tool feeding mechanism, and a tool-feeding driving member located on said axial member to 25 turn about the same.
10. In a channeling machine, the combination with a truck, of a main frame, a 30 pivotally supported standard, tool feeding devices on the standard including an upper sprocket wheel and a lower sprocket wheel near the pivotal support of the standard and a sprocket chain connecting the two, and 35 a sprocket chain driving connection between the lower sprocket wheel and the tool actuating device on the truck.
11. In a channeler, the combination with a truck adapted to travel along a trackway, 40 of a standard, means for supporting the same at the side of the truck for tipping adjustment transversely the trackway, a support on which said standard is pivotally mounted for swinging movement lengthwise 45 the trackway, an axial member projecting rearwardly from said standard in line with the axis of said pivotal support and movable with said standard when the latter is tipped, tool feeding devices on the standard 50 and a power transmission device for said tool feeding devices mounted to turn upon said axial member.
12. In a channeler, the combination with a truck, of a trunnion bar thereon, a standard 55 adapted to be positioned at either end of said trunnion bar, tool feeding devices on said standard, a sprocket wheel on said standard, means for transmitting movement from said sprocket wheel to said tool feeding devices, a sprocket wheel on the truck, a 60 sprocket chain connecting said sprocket wheels, and a frame adjustably mounted on said trunnion shaft and carrying guiding means engaging said chain.
13. In a channeler, the combination with a truck of a standard, means supporting the same for tipping adjustment at the side of the truck, tool feeding devices on the standard, tool feeding devices on the truck, power transmission means connecting the devices 65 on the truck with the devices on the standard, and a guiding frame for said power transmission means also adjustably mounted at the side of the truck.
14. In a channeler, the combination with a truck, of a trunnion bar thereon, a standard supported for tipping adjustment on said bar and for movement about a transverse axis, tool feeding devices on the standard, tool feeding devices on the truck, flexible 70 power transmission means connecting the devices on the truck with the devices on the standard, and a support for said power transmission means adjustably mounted on said trunnion bar.
15. In a channeler, the combination with a truck, of a standard adjustably mounted at the side thereof and adapted to be positioned at either end of the aforesaid truck, tool feeding devices on the standard, power 75 transmission means for said tool feeding devices, and guiding means arranged midway the ends of the truck for said power transmission means.
16. In a track channeler, the combination with a truck, a channeling tool, means for swinging the tool through movement of the truck, means for holding the tool fixed when required, and truck driving mechanism including change speed gears having a sliding gear element for driving the truck at different speeds whereby the truck may be driven at one speed with the tool held fixed and at another speed when the tool is held for swinging movement.
17. In a track channeler, the combination with a truck, truck driving mechanism including a main drive shaft having a main driving gear, a driven shaft, a countershaft driven from the said main shaft and provided with a driving pinion and a driven gear on said driven shaft adapted to be slid into engagement with either said driving pinion or said main driving gear a channeling tool, and means for swinging the tool through movement of the truck, whereby the speed ratio when swinging the tool may be different from that when driving the truck with the tool at rest.
18. In a track channeler, the combination with a truck, of a tool, means for swinging the tool through movement of the truck, and truck driving mechanism including a driven shaft, a sliding gear thereon, and a plurality of driving gears with which said sliding 125

- gear is adapted to be separately engaged whereby the movement of the truck while swinging the tool may be changed over that while traveling with the tool at rest.
19. In a channeler, the combination with a support, of a standard, a tool, said standard being pivoted upon said support for swinging movement, an axial brace rod for said standard pivotally connected to the support, an inclined brace rod connected to the standard and the axial brace rod, a block on said axial rod to which said inclined brace rod is connected, a fixed member having an arc-shaped slot on said support, a nut adapted to slide in said slot, and a clamp hanger on said axial brace rod adapted to be clamped to said nut.
- 15 20. In a channeler, the combination with a

support, a standard movably mounted thereon for adjustment to different positions on the support, a rearwardly extending brace member for said standard pivotally supported on the support, a fixed frame member to which said rearwardly directed member is adjustably secured, and means for securing said brace member to said fixed member comprising a member having a perforation to receive said brace member and a transverse perforation to receive a clamping member.

In testimony whereof I have signed my name to this specification in the presence of two subscribing witnesses.

HENRY H. MERCER.
